UNITED STATES PATENT OFFICE.

JOHN COONEY, OF TORONTO, ONTARIO, CANADA.

SASH-BALANCE.

SPECIFICATION forming part of Letters Patent No. 364,486, dated June 7, 1887.

Application filed February 2, 1887. Serial No. 226,294. (No model.)

To all whom it may concern:

Be it known that I, JOHN COONEY, of the city of Toronto, in the county of York, in the Province of Ontario, Canada, carpenter, have 5 invented a certain new and useful Improvement in Window-Sash Balances, of which the following is a specification.

This invention relates to sash-balances; and it consists in the peculiar combinations and 10 the novel construction, arrangement, and adaptation of parts, all as more fully herein-after described and claimed.

Figure 1 is a perspective view of a window having its sashes balanced according to my invention. Figs. 2 and 3 are cross-sections of 15 same.

I am aware that window-sashes have been arranged prior to my invention so as to balance each other; but in all balances with which 20 I am familiar they can only either be applied to box-frames, or, owing to the manner in which they were applied, it is necessary to cut away a portion of each sash.

In the drawings, A represents two pulley-brackets, which are inserted, as shown, into 25 recesses made in the top sill, B.

A rope, C, passes over each pulley, and its ends are connected to the upper and lower sashes, D and E, respectively.

From this description it will be seen that 30 my device may be very readily and cheaply applied, and that it is only necessary to cut recesses in the top sill, B, in order to receive the pulley-brackets A, and that owing to the 35 simple manner in which they are thus applied

any handy man can apply them to a window very easily and quickly.

With the view of enabling the upper or lower sash to be operated independent of the other, the end of each rope C is connected to the lower sash, E, by means of a dog, F, which fits through a slot made in the sash E and engages with the notched plate G, secured to the outside of the said sash. The dog F is provided with a ring, H, so that it may be readily 40 adjusted into any of the notches formed in the plate G. In this way either sash may be worked independent of the other, while at the same time they balance each other when the dog F fits into one of the notches in the plate G. 50

I am aware of the Patent No. 95,180, and make no claim to the construction shown therein as forming part of my invention.

What I claim as my invention is—

The combination, with the window frame 55 and sashes, of the pulley-brackets A, ropes C, passed over the pulleys and connected at the ends with the sashes, the slotted notched plate G, secured to the outside of the lower sash, and a dog, F, connected with one end of 60 said rope passed through said slot and engaging said plate, substantially as and for the purpose specified.

Toronto, January 4, 1887.

JOHN ^{his} COONEY.
mark.

In presence of—

J. M. QUINN,
T. J. COONEY.
